(57) **CLAIM**

(**) Term: **15 Years**

The ornamental design for a wireless barbecue thermometer receiver, as shown and described.

(21) Appl. No.: **29/636,364**

DESCRIPTION

(22) Filed: **Feb. 8, 2018**

FIG. 1 is a first perspective view of a wireless barbecue thermometer receiver showing my new design;

(51) LOC (11) Cl. 10-04
(52) U.S. Cl. ..... USPC **D10/57; D10/78**

FIG. 2 is a second perspective view thereof;

(58) **Field of Classification Search**

FIG. 3 is a front elevational view thereof;

USPC D10/57, 78
CPC G01K 2207/02; G01K 2207/04; G01K
2207/06; G01K 2207/08

FIG. 4 is a rear elevational view thereof;

See application file for complete search history.

FIG. 5 is a left side view thereof;

(56) **References Cited**

FIG. 6 is a top plan view thereof;

U.S. PATENT DOCUMENTS

FIG. 7 is a bottom plan view thereof; and,

6,568,848 B1 * 5/2003 Chapman G01K 1/024
340/870.17
7,201,099 B2 * 4/2007 Harris, Jr. G01K 1/02
374/E1.002

FIG. 8 is a third perspective view showing the wireless barbecue thermometer receiver in a use state.

The broken lines in the drawings illustrate portions of the wireless barbecue thermometer receiver which form no part of the claimed design.

The diagonal lines in the drawings indicate transparency.
